FACE PLATE FOR GOLF CLUBS

Lynn A. Davis, Jr., Springfield, Mass., assignor to A. G. Spalding & Bros., Inc., Chicopee, Mass., a corporation of Delaware

Filed July 15, 1960, Ser. No. 61,369

Term of patent 14 years

(Cl. D34—5)

Fig. 1

Fig. 2 is a front view of the face plate; and

Fig. 3 is an end view of the face plate.

The dominant features of my design reside in the portions shown in full lines.

The dotted head is shown to disclose the environment of the face plate, said face plate being characterized by elements of contrasting color at the top and bottom thereof with their opposed edges being inclined toward the center and forming a dumbbell-shaped element therebetween extending for the full width of the face.

I claim:

The ornamental design for a face plate for golf clubs, as shown and described.
